UNITED STATES PATENT OFFICE.

MICHAEL J. REILLY, OF CHICAGO, ILLINOIS.

IRONING-MACHINE.

1,359,745.

Specification of Letters Patent: Patented Nov. 23, 1920.

Application filed September 23, 1918, Serial No. 255,280. Renewed May 3, 1920. Serial No. 378,661.

To all whom it may concern:

Be it known that I, MICHAEL J. REILLY, a citizen of the United States, and a resident of the city of Chicago, county of Cook, and State of Illinois, have invented certain new and useful Improvements in Ironing-Machines, of which the following is a specification.

My invention relates to improvements in ironing machines, and has for its object the provision of improved means for heating and operating the iron thereof.

Other objects will appear hereinafter.

The invention consists in the combinations and arrangements of parts hereinafter described and claimed.

The invention will be best understood by reference to the accompanying drawings forming a part of this specification, and in which—

Figure 1, is a side view shown partially in section of a machine embodying the invention,

Fig. 2, an enlarged section taken on line 2—2 of Fig. 1,

Fig. 3, a section taken on line 3—3 of Fig. 2,

Fig. 4, a section taken on line 4—4 of Fig. 3,

Fig. 5, a front view of the machine shown partially in section,

Fig. 6, a section taken on line 6—6 of Fig. 5,

Fig. 7, an enlarged section taken on line 7—7 of Fig. 5,

Fig. 8, a section taken on line 8—8 of Fig. 7, and

Fig. 9, an enlarged detail section of an electrical plug employed in the construction.

The preferred form of construction as illustrated in the drawings comprises a suitable hollow pedestal or standard 10 having an ironing board support 11 projecting forwardly from one side and supporting an ironing board 11' operated by suitable connections from the driving shaft 12 of the machine. An ironing head 13 is arranged in operative relation with the ironing board 11 and is mounted upon the lower end of a hollow shaft 14 supported on a forwardly extending supporting arm 15 at the top of pedestal 10. Shaft 14 is operated by suitable shafts 16 and 17 from the driving shaft, 55 all substantially as more fully set forth in

my prior Patent No. 1,171,248, granted February 8, 1916.

A lever 18 is pivoted in a suitable bracket 19 on the top of arm 15, and has its rear end connected by a link 20 passing downwardly through pedestal 10 with a rocker arm 21 on a rocker shaft 22 extending transversely through the base of pedestal 10. Rocker shaft 22 carries a rocker arm 23 on the outside of pedestal 10 and connected by 60 a link 24, with rocker arm 25 on a pedal shaft 26 mounted in a bracket 27 on pedestal 10. Pedal shaft 26 carries a pedal 28 for operating the same by the foot of the operator, and whereby lever 18 may be readily 65 operated when desired.

The forward end of lever 18 is provided with a bracket 29 embracing shaft 14 and having slot and pin connections with a collar 30 adjustably and loosely mounted on 75 shaft 14 between adjusting nuts 31 threaded thereon. By this arrangement it will be observed that by means of pedal 28 the shaft 14 may be depressed when desired to carry the ironing head 13 into operative relation 80 with the ironing board 11', and that the normal height of the ironing head 13 may be readily adjusted by manipulating nuts 31.

An electrical plug 32 is mounted in the open upper end of shaft 14 and secured in 85 place by means of set screw 33. Plug 32 carries a collar 34 rotating within an electrical connector head 35 and held in place by a central perforated securing plate 36, as shown. Depending arms 37 are secured to 90 plate 36 and slidably engage under straps 38 on brackets 39 secured to collar 30, which arrangement serves to hold the conductor head 35 from rotation and permits of adjustments of shaft 14 and ironing head 13 by means of 95 nuts 31. The plug 32 is made of insulating material and carries a metallic contact band or ring 40, secured as indicated, to a conductor wire 41 leading to the ironing head 13 through the hollow shaft 14. Plug 32 also 110 carries at its top a contact nut 42 electrically connected with another wire 43 also leading to the ironing head 14, as shown. A spring contact finger 44 is mounted in head 35 to contact with the periphery of ring 40 to 105 make electrical connection therewith, and a supply wire 45 leads to the contact 44, as shown. A spring contact 46 contacts with the upper end of nut 42 and is likewise connected with an electrical supply wire 47. By 110

this arrangement it will be observed that electrical current will be supplied to the wires 41 and 43 while permitting of rotation of shaft 14 and vertical reciprocation there-
5 of in the ironing process.

The ironing head 13 is provided with a removable cover plate 48, secured to the lower end of shaft 14 and provided with ventilating holes 49. A supporting or mounting element 50 is loosely arranged within the hollow interior of the cylindrical ironing head 13, as shown. The support 50 is substantially cross shaped in horizontal section, having radiating arms, as shown, provided with openings or perforations 51 arranged out of alinement or registration with each other and adapted to receive an electrical heating element 52 in the form of a heating coil, the support 50 being made of insulating and heat resisting material. The ends of heating coil 52 are connected with binding posts 53 mounted upon a disk 54 of insulating and heat resisting material, and wires 41 and 43 are also connected with 25 these binding posts, whereby electric current is supplied to the heating element 52. Another insulating disk 55 is placed on top of disk 54 and is provided with openings passing over binding posts 53, as shown. 30 By this arrangement a simple and efficient heating element is provided for ironing head 13.

In use, the ironing head 13 is heated, as indicated, by means of the electric current. 35 The article to be ironed is then arranged upon the ironing board 11' and the machine started in operation. The ironing head is brought into contact with the article to be ironed by stepping upon the foot pedal 28; 40 and the article to be ironed is reciprocated in contact with the ironing head by the automatic action of the machine.

While I have illustrated and described the preferred form of construction for carrying my invention into effect, this is capable of variation and modification without departing from the spirit of the invention. I, therefore, do not wish to be limited to the precise details of construction set forth, but desire 45 to avail myself of such variations and modifications as come within the scope of the appended claims.

Having described my invention, what I claim as new and desire to secure by Letters 50 Patent is:—

1. An ironing machine comprising an ironing board; a hollow shaft in operative relation therewith; means for rotating said shaft; an electrically heated ironing head 55 at one end of said shaft in operative relation with said board; an electrical connector head at the other end of said shaft; and an electrical connection leading through said shaft from said connector to said ironing head, substantially as described.

2. An ironing machine comprising an ironing board; a hollow shaft in operative relation therewith; means for rotating and reciprocating said shaft; an electrically heated ironing head at one end of said shaft 7 in operative relation with said board; an electrical connector head at the other end of said shaft; and an electrical connection leading through said shaft from said connector to said ironing head, substantially as described.

3. An ironing machine comprising an ironing board; a hollow shaft in operative relation therewith; means for rotating said shaft; an electrically heated ironing head 80 at one end of said shaft in operative relation with said board; an electrical connector head swiveled at the other end of said shaft; and an electrical connection leading through said shaft from said connector to said iron- 85 board, substantially as described.

4. An ironing machine comprising an ironing board; a hollow shaft in operative relation therewith; means for rotating and reciprocating said shaft; an electrically heated ironing head at one end of said shaft 90 in operative relation with said board; an electrical connector head swiveled at the other end of said shaft; and an electrical connection leading through said shaft from said connector to said ironing head, substantially as described.

5. An ironing machine comprising an ironing board; a hollow shaft in operative relation therewith; means for rotating said 100 shaft; an electrically heated ironing head at one end of said shaft in operative relation with said board; a plug secured in the other end of said shaft and having electric contacts thereon; an electrical connection leading through said shaft from said plug to said ironing head; a non-rotating electrical connector head in operative relation with said plug and having electric contacts slidably connecting with those on the plug; and 110 electric wires leading to the contacts on said connector head, substantially as described.

6. An ironing machine comprising an ironing board; a hollow shaft in operative relation therewith; means for rotating and reciprocating said shaft; an electrically heated ironing head at one end of said shaft 115 in operative relation with said board; a plug secured in the other end of said shaft and having electric contacts thereon; an electrical connection leading through said shaft from said plug to said ironing head; a non-rotating electrical connector head in operative relation with said plug and having electric contacts slidably connecting with those on the plug; and electric wires leading to the contacts on said connector head, substantially as described.

7. An ironing machine comprising an ironing board; a hollow shaft in operative 120

relation therewith; means for rotating said shaft; a hollow ironing head at one end of said shaft in operative relation with said board; a mounting body of insulating material positioned within said ironing head body and having radiating flanges, there being non-aligning perforations in said flanges; an electrical heating coil mounted on said body passing through the perforations in said flanges; an electrical connector head at the other end of said shaft; and electrical connections leading through said shaft from said connector to the heating coil in said ironing head, substantially as described.

8. An ironing machine comprising an ironing board; a hollow shaft in operative relation therewith; means for rotating and reciprocating said shaft; a hollow ironing head at one end of said shaft in operative relation with said board; a mounting body of insulating material positioned within said ironing head body and having radiating flanges, there being non-aligning perforations in said flanges; an electrical heating coil mounted on said body passing through the perforations in said flanges; an electrical connector head at the other end of said shaft; and electrical connections leading

through said shaft from said connector to the heating coil in said ironing head, substantially as described.

9. An ironing head for ironing machines comprising a hollow body; a mounting body of insulating material within said hollow body and having radiating flanges, there being non-aligning perforations in said flanges; and an electrical heating coil on said body and passing through said perforations, substantially as described.

10. An ironing head for ironing machines comprising a hollow cylindrical body; a mounting member of insulating material resting loosely within said body and substantially cross-shaped in transverse section, there being non-aligning perforations in the arms of said body; and an electrical heating coil supported on said body and passing through said perforations, substantially as described.

In testimony whereof I have signed my name to this specification in the presence of two subscribing witnesses.

MICHAEL J. REILLY.
